UNITED STATES PATENT OFFICE.

MONTAGUE H. CLEAVER, OF NEW YORK, N. Y.

COMBINED NON-SKID AND TRACTION DEVICE FOR DUAL-TIRED WHEELS.

1,324,495.

Specification of Letters Patent.

Patented Dec. 9, 1919.

Application filed May 13, 1916. Serial No. 97,438.

To all whom it may concern:

Be it known that I, MONTAGUE H. CLEAVER, a subject of the King of Great Britain, residing at New York city, borough 5 of Manhattan, county and State of New York, have invented certain new and useful Improvements in Combined Non-Skid and Traction Devices for Dual-Tired Wheels, of which the following is a specification.

My invention relates to anti-skid devices for vehicle wheels having dual elastic tires such as are commonly used on motor trucks and comprises an improved form of shoe 15 designed to be securely but flexibly held on such wheels in proper position, and means for so holding a series of such shoes over and across the tread faces of the tires at a predetermined angle and preventing them from 20 being angularly displaced from such position.

Heretofore it has been proposed to form such apparatus of a plurality of rigid shoes of plate form or cruciform shape held together in an endless band or loop by flexible chains or pivoted bar links, the central portions of each shoe lying in the groove between the dual tires, and wings laterally projecting therefrom extending over the 30 tread faces of the tires. The shoes being, however, usually formed of rigid castings, forgings, or stamped-out plates have developed an undesirable tendency to slip circumferentially around the tires under the 35 influence of tractive forces applied to the wheels, especially when there is snow on the ground which is apt to pack in between the shoe and the tire. This tendency to slip circumferentially on the wheel has been aggravated in former constructions by making the central portion of the shoe considerably longer (circumferentially of the wheel) than are the wing or tread portions, the result being a long anti-friction bearing of 40 the shoe on the central and most rigid portion of the wheel face. This central portion of the old form of shoe has been thus made longer than the other portions for a variety of reasons, the principal one being that when 45 flexible connections are used, such long central portion serves to hold the shoe more firmly against angular displacement. An-

other difficulty with the old form of forged, cast or plate construction of solid shoe has developed from their tendency to produce 55 a pounding or chattering effect on the wheel when running over a hard pavement, and also liability to fracture under such pounding.

My present invention avoids these difficulties and secures certain added advantages by substituting for the solid form of shoe one built up of a plurality of matted, twisted or interwoven wires, or wire ropes, preferably mounted in or on a short central 60 bar or body which lies in the groove between the tires, while the wires project in foliaceous form over the tread surfaces of the tires. I also prefer to employ as fastening 65 means chains formed of a series of short eye-bars pivoted together and to the shoes by pivot pins whose axes are parallel to the axis of the wheel, as I am thus able to reduce the length of the central portion of the 70 shoe to the same length as or less than that 75 of the wings or lateral portions of the shoe without danger of the shoe twisting angularly while in use. This chain being flexible only in the plane of the loop formed by the 80 endless chain of links and shoes, it is evident that the shoes cannot twist out of their proper predetermined position on the face 85 of the wheel.

The best form of apparatus at present known to me embodying my invention is 85 illustrated in the accompanying drawings in which—

Figure 1 is a plan view of a portion of a double tired wheel with my invention applied thereto.

Fig. 2 is a vertical section on line 2—2 of Fig. 1.

Fig. 3 is a cross section on line 3—3 of Fig. 1 showing the position of the parts on the road surface, and

Fig. 4 is a detail view of a modified form of shoe.

Throughout the drawings like reference characters indicate like parts.

1, indicates the wheel felly on which are 100 mounted the dual elastic tires 2, 2, the cross sections of which are such as to leave the groove 3, between them. As shown, each shoe is mainly composed of a plurality of

stiff wires or pieces of wire rope 4, 4, which are fastened in or on a short bar 5, adapted to lie in groove 3.

In the preferred construction shown the 5 bar 5 has a long transverse slot 6, formed in it through which the sections of wire rope pass so as to project equally and evenly on both sides, being matted or interwoven or twisted into foliaceous form. The wings 10 thus formed extend across the tread faces of the tires and the free ends of the wires or bits of wire rope are held together in proper position by being welded into end clips, 7, 7. The wires are held in the slot 15 6 by friction, or by welding or soldering or otherwise fastening them therein.

In the form shown in Fig. 4 the wires are compressed laterally or gathered in at the point where they pass through bar 5, so as 20 to render it possible to make the bar 5 shorter than the corresponding element in the form of my invention shown in the other figures of drawing.

Each end of bar 5 is provided with 25 perforated lugs 8, 8, by which it may be pivoted to ends of short sections of chain formed of plate links, 9, 9, all the parts being pivoted together by pins 10, 10. In order to form a chain which shall be extra strong to resist 30 lateral compression and any bending forces exerted in planes other than the plane of the loop formed by shoes and connecting chains, *i. e.* the plane at right angles to pivots 10, 10, I prefer to use double links placed side by 35 side, as shown at 9, 9. Any suitable form of take-up for slack in the chain may be employed such as the turnbuckle 11.

In the form shown in Figs. 1 to 3, the slot 40 6 is as long as the circumferential dimension of the body 12 of the shoe formed of the wires 4, 4. In Fig. 4 I have shown a form in which the bar link 5, and its slot 6, are shortened up, and the wires 4, 4, gathered in at the middle where they pass 45 through the slot. This gives the desirable effect of making bar link 5 as short as possible.

In use the device is applied to a wheel, as 50 shown in the drawings, with the short bars, 5, and connecting chains resting in groove 3, and the wings 12 of the shoe extending across and beyond the tread faces of the tires 2, 2, so that the end pieces 7, 7, will not be compressed. By removing the pivot pin 55 from one end of the turn buckle 11, it may be lengthened or shortened sufficiently to have the endless chain formed by links and bars 5, 5, rest securely in groove 3, but without binding therein. As a result the shoes 60 may creep slowly around the wheel when in use, but cannot become detached therefrom. The eye-bar connections hold the shoes firmly so that the major axis of each remains parallel to the major axes of all the

others, and they cannot twist or turn from 65 that position. This prevents the shoes from unseating themselves by twisting about on the surfaces of the tires, or canting over toward either side, while at the same time they are free to move radially of the wheel as the 70 elastic tires yield under pressure.

Further advantages arise from the flexible character of the shoe treads which are preferably formed of stiff, but slightly flexible and very tough steel wire, which yield to the 75 inequalities of the road and embed themselves in the yielding surfaces of the tires, getting a firm grip on both and avoiding all pounding or chattering even when used upon the hardest pavements. Moreover these 80 foliaceous wings of woven or matted wire do not score the roadbed as severely as do solid, cast or forged shoes when used on heavy trucks.

Various changes could be made in the arrangement of the wires forming the shoe tread without departing from the principle of my invention so long as the results above described are kept in view.

Having described my invention, I claim: 90

1. A shoe for use in an anti-skidding device for wheels having dual elastic tires, which is formed of a series of stiff but slightly flexible wires extending side by side and of a length sufficient to reach across the 95 tread faces of the tires, together with means for fastening together said wires along a line transverse thereof and midway of their lengths.

2. A shoe for use in an anti-skidding device for wheels having dual elastic tires comprising in combination a central bar adapted to lie in the groove between the tires and provided with chain attaching means at each end, and wings of wire rope extending 105 on either side of said bar and adapted to rest on the tread faces of the tires.

3. A shoe for use in an anti-skidding device for wheels having dual elastic tires which comprises in combination a central 110 bar having a transverse perforation, a plurality of short bits of wire rope extending through said perforation and fastened therein so as to form foliaceous extensions on either side of the bar, and means fastening 115 together the free ends of the said bits of wire rope and holding them assembled.

4. A shoe for use in an anti-skidding device for wheels having dual elastic tires which consists of the combination of a short 120 bar having a transverse slot therethrough and perforated lugs projecting from each end, adapted to lie in the groove between the tires, a plurality of short pieces of wire rope held in said slot and interwoven to form a 125 flat band projecting from either side of the bar and extending across the treads of the tires, and strips of metal welded to the free

ends of the wire ropes at points beyond the outer edges of the tire treads, whereby the tread portions of said shoe are formed entirely of interwoven bits of wire rope.

5. A shoe for use in an anti-skidding device for wheels having dual elastic tires which has a central body adapted to lie in

the groove between the tires, and stiff but slightly flexible flat wings projecting from either side of said central body adapted to 10 overlap the treads of both tires, said wings being formed of a plurality of slightly flexible wires.

MONTAGUE H. CLEAVER.
